US0D1069010S

(12) **United States Design Patent** (10) **Patent No.:** **US D1,069,010 S**
(45) **Date of Patent:** **** Apr. 1, 2025**

(54) **HUB SHELTER**

(71) Applicant: **DLX Enterprises, LLC**, Eugene, OR (US)

(72) Inventors: **Jonathan Urhausen**, Eugene, OR (US); **Adam Barr**, Eugene, OR (US); **Donald Bierman**, Eugene, OR (US)

(73) Assignee: **DLX Enterprises, LLC**, Eugene, OR (US)

(**) Term: **15 Years**

(21) Appl. No.: **29/849,224**

(22) Filed: **Aug. 9, 2022**

Related U.S. Application Data

(63) Continuation of application No. 17/857,732, filed on Jul. 5, 2022, now Pat. No. 11,939,785, which is a continuation of application No. 17/677,210, filed on Feb. 22, 2022, now Pat. No. 11,898,366, which is a continuation of application No. 16/861,012, filed on Apr. 28, 2020, now Pat. No. 11,280,107.

(57) **CLAIM**

The ornamental design for a hub shelter as shown and described.

DESCRIPTION

FIG. 1 is a side perspective view of a hub shelter showing my new design;

FIG. 2 is a front view thereof;

FIG. 3 is a back view thereof;

FIG. 4 is a side view thereof;

FIG. 5 is another side view thereof; and,

FIG. 6 is a top view thereof.

The broken lines are for the purpose of illustrating portions of the hub shelter that form no part of the claim.

1 Claim, 6 Drawing Sheets
